UNITED STATES PATENT OFFICE.

ALBERT H. STEBBINS, OF LOS ANGELES, CALIFORNIA.

OPERATING MEANS.

Application filed May 15, 1928. Serial No. 277,915.

This invention relates to means for imparting progressive vibratory movements to frames and other devices supported for vibratory movement.

5 Various devices such as screens, concentrator tables and other forms of separators employ a progressive vibratory movement in effecting separation of the materials being treated.

10 Eccentrics have been extensively used heretofore to develop a vibratory movement, but the ordinary eccentric does not produce a progressive vibratory movement as it will merely move the device being vibrated back and forth as energetically in one direction as in the other. Various constructions have therefore been proposed heretofore to modify the action of an eccentric to cause the same to develop a progressive vibratory movement.

15 Such devices for developing progressive vibratory movement should be so constructed that they will not be readily injured by the dirt and dust produced by the screens or separator being vibrated and should be simple in construction and strong and durable.

20 The present invention therefore relates to an extremely simple construction for modifying the action of an eccentric to produce the desired progressive movement, and in carrying out the present invention cables are associated with a power driven eccentric in such a way that one cable is tensioned as the other is slackened off to thereby pull the vibratory frame back and forth, and the progressive movement is produced by a spring which serves to modify the turn at one end of the path of travel.

25 More specifically the present invention resides in operating means for developing a progressive vibratory movement and consists of a positively anchored cable for pulling the frame in one direction, a yieldingly anchored cable for pulling the frame in the opposite direction, a power driven eccentric for tensioning and slackening off said cables, and a spring that cooperates with the positively anchored cable to move the frame in the direction of the progressive movement beyond the throw of the eccentric so that the yieldingly anchored cable will pull the frame back with a quick snap which will advance the materials being treated in the desired direction.

30 The various features of the invention and novel combination of parts will be best understood from the following description when

read in connection with the accompanying drawings which illustrate good practical forms of the invention.

In the drawings,—

Fig. 1 is a side elevation of a machine provided with operating means constructed in accordance with the present invention;

Fig. 2 is a perspective view of the operating mechanism of Fig. 1;

Fig. 3 is a side elevation of a modification of the construction of Fig. 1;

Fig. 4 is a side elevation of a second modified form of operating means;

Fig. 5 is a top plan view of the operating mechanism of Fig. 1, the vibratory frame being omitted; and

Fig. 6 is a diagrammatic view illustrating the nature of the movement imparted to the vibratory frame.

The novel mechanism of the present invention for developing a progressive vibratory movement may be employed for various purposes and is shown in the drawings as adapted to impart progressive vibratory movement to a frame 10 which frame may constitute a concentrator deck, screen or other form of separator employing a progressive vibratory movement to advance the materials being treated lengthwise of the frame 10.

Any appropriate means may be employed for supporting the frame 10 for vibratory movement in the direction of its length and this frame is shown in the drawings as mounted upon a casing or supporting structure having the uprights 11 to which the longitudinally extending beams 12 are secured and the uprights 11 are connected by the transversely extending braces 13. Upon the supporting structure are mounted the bearing blocks 14 which in the present case are shown as having ball receiving grooves or recesses formed in their upper faces to receive the balls or rollers 15 adapted to support similarly constructed bearing blocks 16 secured to the under face of the frame or carriage 10, the construction being such that the frame 10 is supported for vibratory movement in the direction of its length.

The mechanism forming the subject matter of the present invention for imparting a progressive vibratory movement to the frame 10 will now be described, and in the construction shown consists of a cable 17 one end of which is rigidly secured to a block 18 or other form of fastening means attached to the under face

of the vibratory frame 10. The cable 17 extends in a right-hand direction, in the construction shown, about an idle grooved sheave 19 which is rotatably supported by a transversely extending shaft 20 that is mounted upon the casing or supporting structure. The cable 17 extends from the lower side of the sheave 19 about a grooved sheave 21 which is journaled upon an eccentric 22 which eccentric is rigidly secured to the transversely extending power shaft 23. This power shaft is journaled in bearings 24 mounted upon the supporting structure and the shaft may be rotated by a pulley 25.

15 The portion of the cable 17 extending in a right-hand direction from the lower side of the sheave 21 is positively or nonyieldingly secured to a transversely extending brace 26 of the supporting structure, and to this end 20 the cable is secured to a threaded bolt 27 provided with the adjustable nuts 28 which may be adjusted to vary the tension or effective length of the cable 17. When the power shaft 23 is rotated the eccentric 22 will turn within 25 the grooved sheave 21 and will move the sheave bodily in an orbital path to thereby tension and slacken off the cable 17, the arrangement being such that when the eccentric 22 is turned to the position in which it 30 is shown in Fig. 2, it will tension the cable 17 to pull the frame 10 in a right-hand direction.

Movement of the frame 10 in a left-hand direction is effected in accordance with the present invention by a cable 29 one end of 35 which is secured to the transversely extending block 18 and the cable extends in a left-hand direction from this block about a grooved idle sheave 30 which is rotatably supported by 40 the transversely extending shaft 31. The cable 29 extends from the lower side of the sheave 30 about a second grooved sheave 32 which is journaled upon the eccentric 22, and the end portion of this cable 29 extends from 45 the under side of the sheave 32 to a transversely extending brace 33 to which it is yieldingly secured, this being accomplished in the construction shown by attaching the end of the cable 29 to a threaded bolt 34 upon which a 50 coiled spring 35 is mounted, this spring being confined between a face of the transversely extending brace 33 and the adjustable nuts 36 mounted upon the bolt 34.

55 As a result of the operating mechanism so far described the frame 10 will be pulled back and forth with a vibratory movement by the cables 17 and 29 since the sheaves 21 and 32 mounted upon the eccentric 22 will tension one cable as the other cable is slackened off, 60 and the vibratory movement imparted to the frame 10 by this form of operating means may be more or less progressive, depending upon the strength and tension of the spring 35. The operating mechanism so far described is similar to that shown, described

and claimed in the Albert H. Stebbins Patent No. 1,593,731, dated July 27, 1926, but it may be desirable to employ a more energetic progressive vibratory movement than that produced by the construction so far described, 70 and this is accomplished, in accordance with the present invention, by providing an auxiliary spring which will cooperate with the positively anchored cable 17 to move the frame 10 more energetically in the direction 75 of the progressive vibratory movement than in the opposite direction. Various constructions may be provided employing this auxiliary spring, one construction thereof being shown in Fig. 2, a second construction being 80 shown in Fig. 3, and still a third construction is shown in Fig. 4. The construction disclosed in Fig. 3 is quite simple and will be first considered.

The auxiliary spring 37 shown in Fig. 3 85 is mounted so that one end of this coiled spring rests against a block or flanged plate 38 rigidly secured to the under face of the frame 10 and the opposite end of this spring abuts against a socket plate 39 which is secured to a rod or bolt 40 and this bolt is adjustably mounted in a bracket 41 which is rigidly secured to the supporting casing. Since an eccentric 22 is employed to tension 90 and slack-off the operating cables 17 and 29 95 the movement imparted to the frame 10 will gradually increase from one end of its stroke to its central position and then gradually decrease from its central portion to the opposite end of its stroke and the turn at the ends of 100 the stroke will be relatively slow and smooth, unless such turn is modified by springs or other operating mechanism. As the cable 17 has its ends non-yieldably secured to the block 18 and anchoring devices 26 this cable will 105 limit the movement of the frame 10 in the left-hand direction to the configuration of the operating eccentric, and as the frame 10 reaches the end of its stroke the change in direction will be relatively smooth, due to the 110 fact that the eccentric 22 at this instant is passing through the dead centre position in which it is shown in Fig. 3.

As the frame 10 approaches the end of its stroke in a right-hand direction it is desirable to impart a snap or quick reversal of the direction of movement to the frame, to thereby advance the materials being treated lengthwise of the frame 10 in a right-hand direction. This is accomplished by providing the auxiliary spring 37 which cooperates with the positively anchored cable 17 to increase the speed at which the frame 10 is moved in a right-hand direction, and as a result the increased momentum of the frame 10 in this direction will carry the frame somewhat beyond the normal end of its stroke in the right-hand direction. This additional movement will be permitted by the spring 35 which constitutes a yielding anchor for the cable 29. This addi- 115 120 125 130

tional movement, however, will place the spring 35 under abnormal tension with the result that this spring acting through the cable 29 will serve to jerk the frame 10 backward 5 quickly in the left-hand direction, thereby imparting the desired snap or quick turn to the frame 10 to advance the materials lengthwise of the frame in a right-hand direction.

The operation of the mechanism just described will be more clearly understood upon reference to Fig. 6 in which this form of movement is illustrated diagrammatically.

In Fig. 6 the power shaft 23 is shown as having the eccentric 22 and upon this eccentric 15 is mounted the grooved sheave 21.

It is apparent that if the auxiliary spring 37 and the spring for yieldingly anchoring the cable 29 to the supporting structure were omitted from Fig. 3, then a non-progressive 20 movement would be imparted to the frame 10 and the nature of this movement would be indicated by the circle 42 of Fig. 6 and the change in the speed of movement imparted to the frame 10 at successive intervals in its path 25 of travel would be indicated by the vertical lines 43. Through the employment of the springs 35 and 37 whereby the momentum of the frame 10 in a right-hand direction is increased, the frame will move beyond the 30 throw of the eccentric in this direction, as indicated by the curve 44 and will then be snapped back quickly at the end of its stroke as indicated by the short, steep curve 45, and at this instant the desired progressive movement 35 will be imparted to the materials being treated upon the frame 10.

In Fig. 2 the auxiliary spring 46, instead of being arranged the same as the spring 37 of Fig. 3, is attached to the lower end of a third cable 47 which cable, as will be apparent from Fig. 2, passes around a third sheave 48 mounted upon the eccentric 22 and then about a second sheave 49 upon the shaft 20, and the upper end of this cable is rigidly secured to the block 18. The effect of this arrangement 45 will be the same as that of the spring 37 of Fig. 3 since the spring 46 will act upon the cable 47 to speed up the movement of the frame 10 in a right-hand direction, to produce the desired quick turn at the end of the stroke 50 in this direction as above described.

This same result may be secured by the third arrangement of the auxiliary spring shown in Fig. 4, wherein the spring 50 is positioned to exert an upward force upon the shaft or bolt 51; this spring being confined between a transversely extending brace 52 and adjustable nuts 53 provided upon the bolt 51. The lower end of the bolt 51 is provided 60 with a hollow block 54 through which the lower portion of the positively anchored cable 17 extends, as will be apparent from Fig. 4. The effect of this arrangement is that the spring 50 will exert a continuous upward 65 pull upon the lower horizontally extending

portion of the cable 17 to displace this portion of the cable upwardly. This upward pull will serve to speed up the movement of the frame 10 in a right-hand direction which as above pointed out is desired to impart the 70 quick turn to the frame 10 at the right-hand end of its stroke.

The auxiliary spring in each case obviously should be of less strength than the anchoring spring 35, for otherwise the spring 35 would 75 fail to pull the frame 10 in a left-hand direction with sufficient force to keep the positively anchored cable 17 taut. If the frame 10 being operated is relatively heavy additional cables may obviously be provided to relieve 80 the cables 17, 29 and 47 from excessive strains.

It will be apparent from the foregoing that the present invention is extremely simple in construction, and that the mechanism employed is strong and durable and is not likely 85 to be injured by the dirt and dust which commonly attends separating operations.

What is claimed is:—

1. In combination with a frame supported for vibratory movement, operating means 90 for imparting progressive vibratory movement to the frame, comprising an eccentric shaft, a sheave mounted upon the eccentric, a cable extending around one side of the sheave and having one end anchored and its 95 other end secured to the vibratory frame, a second cable extending around the opposite side of the sheave and having one end secured to said frame and its other end secured to a yielding anchor, means for rotating said eccentric, and an auxiliary spring arranged to increase the velocity of the movement of said frame in a direction to momentarily extend said yielding anchor as the frame reaches the 100 end of its stroke in the direction of the progressive movement.

2. In combination with a frame supported for vibratory movement, operating means for 110 imparting progressive vibratory movement to the frame, comprising a positively anchored cable for pulling the frame in one direction, a yieldingly anchored cable for pulling the frame in the opposite direction, a power driven eccentric for alternately tensioning and slackening off said cables, and an auxiliary spring for increasing the velocity 115 of the movement of the frame in a direction to momentarily increase the pull upon said yieldingly anchored cable as the frame reaches the end of its stroke in one direction. 120

3. In combination with a frame supported for vibratory movement, operating means for 125 imparting progressive vibratory movement to the frame, comprising a positively anchored cable for pulling the frame in one direction, a yieldingly anchored cable for pulling the frame in the opposite direction, a power driven eccentric for alternately tensioning and slackening off said cables, and an auxiliary spring arranged to cooperate with 130

said positively anchored cable to move the frame with increased energy in the direction to momentarily increase the pull upon said yieldingly anchored cable as the frame reaches the end of its stroke in the direction of the progressive movement.

4. In combination with a frame supported for vibratory movement, operating means for imparting progressive vibratory movement to the frame, comprising a positively anchored cable for pulling the frame in one direction, a yieldingly anchored cable for pulling the frame in the opposite direction, a power driven eccentric for alternately pulling the cables back and forth to move the frame along a path corresponding to the throw of said eccentric, and an auxiliary spring adapted to cooperate with said positively anchored cable to move the frame in the direction of the progressive movement beyond the throw of said eccentric to cause the yieldingly anchored cable to pull the frame back with a quick snap.

5. In combination with a frame supported for vibratory movement, operating means for imparting progressive, vibratory movement to the frame, comprising an eccentric, a cable extending around one side of the eccentric and having one end anchored and its other end secured to the vibratory frame, a second cable extending around the opposite side of the eccentric and having one end se-

cured to said frame and its other end secured to a yielding anchor, means for rotating the eccentric to move the frame along a path corresponding to the throw of said eccentric, and an auxiliary spring arranged to cooperate with said positively anchored cable to move the frame in the direction of the progressive movement beyond the throw of said eccentric to cause the yieldingly anchored cable to pull the frame back with a quick movement.

6. In combination with a frame supported for vibratory movement, operating means for imparting progressive vibratory movement to the frame, comprising an eccentric, a cable extending around one side of the eccentric and having one end anchored and its other end secured to the vibratory frame, a second cable extending around the opposite side of the eccentric and having one end secured to said frame and its other end secured to a yielding anchor, means for rotating the eccentric to actuate the cables to pull the frame back and forth, and a third cable extending around said eccentric and provided with a spring that acts upon the frame to increase its travel in the direction of the progressive movement.

In testimony whereof, I have signed my name to this specification.

ALBERT H. STEBBINS.
